UNITED STATES PATENT OFFICE.

FRED HILDRETH CHAPMAN, OF PEPPERELL, MASSACHUSETTS, ASSIGNOR TO ACME
BALL BEARING SPINDLE COMPANY, OF FRANKLIN, NEW HAMPSHIRE, A COR-
PORATION OF NEW HAMPSHIRE.

SPINDLE AND BASE.

Application filed April 22, 1926. Serial No. 103,826.

This invention relates to spindles of the sort used in machines for spinning or twisting yarn, thread, etc. and is particularly adapted to ball bearing spindles of the type shown in my prior Patents Nos. 1,253,351; 5 1,338,904; 1,406,975, and my pending application, Serial No. 750,212, filed November 15, 1924; although it is not limited to ball bearing spindles, but is applicable as well to those 10 of the common and widely used type having a plain bearing for the spindle blade.

The object of the invention is to provide a spindle base that may be cast with its longest dimension vertical; one having no obstructions in such a position as would interfere with tying a driving band and applying it to the spindle; to provide as a part of such base an extended flange at the front side having an oil pocket communicating with the interior of the base and so disposed that oil 20 may be poured into it when the ring rail of the spinning machine is in its lowered position, and the spindles of adjacent spinning frames may be oiled by an attendant while 25 making a single trip through the passage between them; to provide such spindle base with a hinged plate carrying a stop pin and forming a cover for the oil pocket, constructed and arranged so that it may be raised 30 high enough to give a good view of the pocket when oiling; and to avoid all extensions which would interfere with the rods 35 operating the ring rail, or would necessitate placing the spindle base in an awkward position to avoid such interference.

Spindles of the type adapted for spinning yarn and thread and in general use at the present day are made of cast iron and have oil stems at one side of the axis rising to a 40 height above the spindle whirl and enlarged at the upper end for mounting a hinged deflector guard. This construction necessitates casting the spindle base with its axis horizontal, owing to the conditions controlling 45 the metal-founder's art. The segregation of the metalloids which occurs in the mold while the iron (or other metal of which the spindle base may be made) is still fluid, causes the lower side of the casting to be denser and 50 harder than the metal at the upper side, and this uneven density causes the drill, by which the socket in the base to receive the spindle blade is afterward cut, to be crowded over to one side of its intended line of feed as it is

fed into the casting, wherefore all spindle bases of the kind in general use, as heretofore made, have interior chambers which are more or less out of line. When the spindle bases are set up in the spinning frame, they must be individually adjusted to bring them and 55 their inserted spindle blades truly vertical, or as nearly so as possible, generally by inserting strips of pasteboard or paper on the spindle rail under the flange of the base at the low side, as may be required in each case. 60 The adjustment and testing of each spindle made necessary by this inaccuracy in the spindle bases as heretofore made, makes the assemblage and setting up of a spindle frame 65 a long, tedious and expensive process.

I am aware that it has been proposed to make spindle bases of a design which would permit of casting them in the perpendicular position; but although such a proposal has been made many years ago, I have not known 70 or heard of any such proposed spindle bases having been put into commercial use, notwithstanding that I have had a long and wide acquaintance with the spinning art. Spindle bases provided with an oil stem are 75 located in the spinning frame with the oil stem partly at one side, in order to give as much space as possible in front to tie the ends of the driving band together below the whirl before passing the band over the whirl. 80 But the space thus afforded is very limited, because the oil stem must be far enough to the front to permit oil to be poured into it, and the stem makes the operation of tying 85 and placing the driving band about the whirl 90 very difficult. Besides having these objections, the oil stem is a cause of additional expense in the original manufacture of the spindle base, due to the necessity of drilling 95 in it a passage communicating with the interior of the base for reception of oil. Yet notwithstanding the objections due to oil stems, the spindle bases heretofore generally, if not universally, used in spinning mills have been provided with them.

I have avoided the objections inherent in the previously used spindle bases, as above described, by providing a new form of base, the characteristics and salient features of which are described in the following specification with reference to the drawings here-with furnished, in which I have illustrated 100 the preferred embodiment of the invention 105

as applied to a ball bearing spindle. The invention consists in the novel characteristics of such base, and the combination thereof with a spindle blade and its whirl, herein-after fully described and claimed.

In the drawings,—

Fig. 1 is a sectional view of a complete spindle including a base in which the present invention is embodied, a blade, a driving whirl for the blade, a stop pin and a cover plate;

Fig. 2 is a plan view of the base;

Fig. 3 is a plan view of the cover plate; and

Fig. 4 is a vertical cross section of the cover plate.

Like reference characters designate the same parts wherever they occur in all the figures.

20 *a* represents the base, *b* the blade, and *c* the whirl applied to the blade. The base is provided with a lateral flange *d*, by which it rests on the spindle carrying rail of the spinning frame, the lower part of the base projecting through the rail, being screw threaded in the part *e* to receive a nut for clamping it to the rail in the usual way. The interior of the base is drilled to form an internal chamber or socket *f* to receive the foot of the 30 blade and a step bearing *g*.

In the present design, the upper part of the base is enlarged to receive a sleeve *h* forming the outer race of a ball bearing *i*, of the character described in my prior application, Serial No. 750,212, previously referred to; but this is a detail which may be departed from; and the essential characteristics of the invention may be applied to the base adapted for a spindle of the common 40 journal-bearing type. The proportions of the spindle blade, base and whirl, and the relation of the whirl to the flange, are, or may be, substantially the same as those existing in spindles of the type and designs now 45 in general commercial use, except that the flange extends at one side of the spindle to a much greater distance than is usual with such spindles.

In the upper horizontal side of the flange *d* 50 is an open pocket *j* to receive oil, and from the inner wall of this pocket a hole *k* leads to the chamber *f*. The pocket and the outer boundary of the flange are preferably concentric with the blade, as shown in plan 55 view by Fig. 2. As previously stated, the flange *d* projects at one side of the spindle to a much greater distance than usual heretofore, and the part so projecting is that in which the oil pocket *j* is contained. It extends so far that the pocket is entirely outside of the circumference of the whirl, or, in 60 other words, it is farther away from the axis of the spindle blade than the circumference of the whirl. When the spindle is 65 applied to the spinning rail of the spindle

frame, the base is set with the oil pocket on the outside or front, (considering as the front the side of the spindle at which the attendant stands when oiling it or performing other duties in connection with the machine). 70 The sides of the base toward adjacent spindles may be flattened, as shown in Fig. 2, in order to permit placement of spindles as near together as permitted by other factors, and the oil pocket may be as long as the 75 distance between these sides less the space needed to provide confining walls at the ends of the pocket.

The base is provided at the rear with a lug *l* to support a pivot pin *m* by which a 80 plate *o* is connected to the base. The plate *o* serves as a cover for the oil pocket and also as a holder for a stop pin *p* or doffer guard; having a rear extension *q* in which the pin is mounted. The central part of the plate 85 is open, or formed with an aperture, to admit the rising part of the base, which provides the bearing for the blade, and the spindle whirl. The rear part of the aperture, designated as *r* in Fig. 3, is complementary to the lug *l*, and elsewhere the aperture is large enough to permit the plate, when raised, to clear the lower flange of the whirl and to be raised high enough to fully uncover the pocket, as shown by dotted lines 90 in Fig. 1, giving a clear view of it to the attendant and leaving ample room for pouring oil into it. The forward part of the plate is of proper dimensions to overlie and fully 95 cover the oil pocket *j* and to extend at its outer rim somewhat beyond the adjacent part of the base flange *d*.

The stop pin *p* rises from the cover plate at the rear of the whirl, where it offers no 100 impediment to tying and applying the driving band, and its upper end is bent over so as to overlie the upper flange thereof and prevent the blade being removed from the base when the bobbin is doffed. But when it is necessary to remove the blade, the stop 110 pin can be shifted out of the way of the whirl by slightly raising the forward side of the plate.

In calling the member *o* a plate, I have 115 not intended to imply a limitation as to its form. In its preferred form, as here shown, it completely surrounds the axis of the spindle, but it may be otherwise formed. That part of it which lies at the front of the base and covers the oil pocket is of 120 short height or thickness and substantially flat on the upper side. The upper surface of the plate, as to this part, is thus located at a substantial distance below the bottom of the whirl, and leaves an open unobstructed space in which the rising part of the base above the flange is exposed.

The part which I have just designated as the rising part of the base is the part which receives and surrounds the sleeve *h*, pre- 130

viously mentioned, and is surrounded at its upper end by the lower part of the whirl. It provides a stationary surface exposed at the front side of the spindle, over which the ends of the driving band may be passed and against which the band may be supported while these ends are tied together, wherefore this part of the base may be termed a band support. This band support

10 is approximately equal in radius to the bottom of the band receiving groove in the whirl, thus enabling a band to be tied with sufficient tension for driving the whirl. The material used for driving bands is suffi-

15 ciently elastic to permit the band, after being so tied, to be passed over the outstanding lower flange of the whirl. This band support enables the driving band of any spindle to be tied without stopping the en-

20 tire spinning frame in which the spindle is mounted, since the stationary surface of the support enables the operator to hold the band stationary while tying the knot, even though the driving drum, around which the

25 band also passes, continues in rotation.

The same support also serves as a means for temporarily holding the band when the blade and whirl are removed for turning the band to drive the spindle in the opposite 30 direction. Its presence in all the spindles of a spinning frame greatly facilitates, and shortens the time necessary for, changing the bands to drive all the spindles oppositely to their previous direction of rotation.

35 It will be understood from the foregoing description that the base can be cast in a vertical position, for it has no projections which would prevent drawing of the pattern from either part of the sand mold in a 40 longitudinal direction. This allows the heavier metalloids of the molten iron to settle symmetrically around the axis of the base and enables the subsequent drilling operation to be carried out easily with perfect truth, and enables the base afterwards 45 to be set up on the rail without adjustment to compensate for any departure of the socket from the true vertical.

The large size of the oil pocket and high 50 lift of the cover makes it possible for the attendant to supply oil even when the ring rail is in its lowermost position, and eliminates the loss of time heretofore experienced on account of the attendant being obliged, in 55 many instances, to wait until the ring rail has risen far enough to allow him to apply the spout of his oil can to the mouth of the oil stem in the prior type spindle. The danger of overfilling the pocket is largely 60 avoided, because the attendant, by noting when the oil ceases to drain out of the pocket as he pours it in, and begins to fill up, can tell that the interior of the base is full of oil, in time to cease pouring before 65 he has overfilled the pocket. Such oil as

then occupies the pocket then provides a reserve supply.

By virtue of the arrangement of the oil pocket at the front of the spindle and its very large area, the attendant, in the course 70 of a single passage through the alley between two adjacent spinning frames, is able conveniently and easily to oil the spindles of both machines; and he is able to place the spout of his oil can in the pocket more readily than he can place it in the orifice of the old type oil stem. All of this conduces to economy of time and oil in keeping the spindles supplied with oil.

75 What I claim and desire to secure by Letters Patent is:

1. A spindle of the character set forth comprising a base, a blade and whirl mounted in the base, said base having a flange with an oil pocket communicating with the blade 80 receiving socket in its top surface at the forward side of the blade, a plate hinged to the base and forming a cover for said oil pocket, and a doffer guard carried by the plate to engage the whirl and located at the opposite 85 side of the hinge axis of the plate from the oil pocket, the base and plate being free from obstruction in the plane of the whirl.

2. A spindle of the character set forth, including a base, a blade and a whirl, said 90 base having a flange with an oil pocket in the upper side of its front portion, and having a stationary rising portion above said flange, and a plate serving as a cover for 95 said oil pocket and hinged to the flange, the plate being entirely below the bottom of the whirl and separated therefrom by a space in which said stationary portion is exposed for supporting the ends of a driving band in being tied together.

100 105 110 115 120 125 130

3. A spindle according to claim 2 in which the mouth of the oil pocket and plate are horizontal and the plate is pivoted at the rear of the whirl, and embraces it, and that part of said plate which covers the oil pocket lies outside of the circumference of the whirl and is adapted to pass across the lower circumference thereof when being raised.

4. A spindle of the character set forth, including a base having an upright band support for supporting the band in being tied, a blade, and a whirl above said band support, said base having a flange with an oil pocket in its front portion below the band support, a plate hinged to the back portion of said flange extending past said band support and having a cover portion overlying said oil pocket below the band support, and a stop pin carried by the plate adjacent to the hinge thereof and projecting over a protuberant part of said whirl.

5. A spindle of the character set forth comprising a base having a lateral flange, a band support for supporting the driving band in being tied, rising above said flange,

- an internal chamber or socket, an oil pocket in the upper face of said flange and a passage leading from said oil pocket to said chamber, a spindle blade rotatably mounted 5 in said base and rising above the same, a whirl carried by the blade and having a pulley portion, a cover pivotally mounted on said base to overlie said oil pocket and extending to the opposite side of the spindle 10 from the pocket, and a stop mounted on the rearwardly extending part of said cover and coacting with said whirl as a doffer guard, said cover being located below the whirl and leaving exposed beneath the latter a portion 15 of the upstanding part of the base, and both the oil pocket and that part of the cover which covers it being located far enough away from the axis of the whirl to permit rise of the said cover part above the lower 20 flange of the whirl pulley when opened.
6. In a spindle of the character described, a base having an internal socket and a lateral outstanding flange, said flange having in its top face an extended oil pocket and 25 containing a passage leading from said pocket to said socket, the rim of said oil pocket being flush with the upper surface of said flange, and a cover for said oil pocket pivoted to the base; the base having a band

support for supporting the driving band when being tied, rising above the upper side of the cover.

7. A spindle for spinning machinery comprising a base having a blade-receiving socket and a lateral external flange, a blade 35 rotatably mounted in said socket, a whirl carried by the blade and located with its lower end at a substantial distance above the top surface of the flange, said flange having a substantially plane horizontal top surface 40 recessed adjacent to its forward edge to form a laterally extending oil pocket and a cover pivoted to the base at the rear side thereof and extending over said pocket, being apertured to embrace that part of the 45 base which receives the spindle, and a doffer guard mounted on the rear part of said cover; the base having an upstanding portion rising above the cover and into the lower part of the whirl, said upstanding 50 portion being free from obstruction at the forward side of the spindle and adapted to be engaged by a driving band for the whirl when the ends of such band are tied together.

In testimony whereof I have affixed my signature.

FRED HILDRETH CHAPMAN.
